[57] CLAIM

The ornamental design for a toy pirate ship, as shown and described.

DESCRIPTION

FIG. 1 is a top left front perspective view of a toy pirate ship showing our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a top left front perspective view thereof, the broken line showing of environmental features is for illustrative purposes only and forms no part of the claimed design.
